UNITED STATES PATENT OFFICE.

CHINTO A. GARZONI, OF DE LANCEY, PENNSYLVANIA.

AIR-HOSE COUPLING.

1,328,373.

Specification of Letters Patent. Patented Jan. 20, 1920.

Application filed November 12, 1918. Serial No. 262,211.

To all whom it may concern:

Be it known that I, CHINTO A. GARZONI, a citizen of the United States, residing at De Lancey, in the county of Jefferson and State of Pennsylvania, have invented certain new and useful Improvements in Air-Hose Couplings, of which the following is a specification.

My invention relates to new and useful improvements in air hose couplings and to that class of couplings particularly used in connection with railway trains, and an important object of which is to provide a device consisting of a pair of coupling members which include means whereby air automatically passes through said members when they are coupled.

Another important object of my invention is to provide a device consisting of a pair of coupling members, each member having a head which is permitted to move longitudinally and swing transversely of a car to which the coupling member is secured and at the same time said head is prevented from rocking with the car when the heads of the two coupling members are coupled.

Another object of my invention is to provide a device including a pair of coupling heads so constructed that the walls of said heads carrying the air outlet ports or passage-ways are held in close engagement with each other when the heads are coupled together.

A further object of my invention is to provide a device including a pair of coupling heads, each head having a normally closed valve therein, which operates longitudinally of said head.

A still further object of my invention is to provide a device of the above named character which is simple and durable in construction, reliable and efficient in operation and one which can be manufactured at a minimum cost.

Other objects and advantages of the invention will be apparent during the course of the following description.

The invention also consists in certain other features of construction and in the combination and arrangement of the several parts to be hereinafter fully described, illustrated in the accompanying drawings and specifically pointed out in the appended claims.

In the accompanying drawing, forming a

part of this specification and in which like numerals are employed to designate like parts throughout the same.

Figure 1 is a side elevation of the invention showing the same attached to the end of a railway car.

Fig. 2 is an end view of the invention looking into the forward end or coupling head of the same.

Fig. 3 is a vertical transverse sectional view of the coupling member taken on the line 3—3 of Fig. 4.

Fig. 4 is a longitudinal sectional top view of the invention.

Fig. 5 is a vertical transverse sectional view taken on the line 5—5 of Fig. 4 and 70

Fig. 6 is an enlarged transverse longitudinal sectional view of a portion of the coupling head.

In the drawings, wherein for the purpose of illustration is shown a preferred embodiment of my invention, the numeral 6 designates a portion of the forward end of a railway car.

My air hose coupling designated generally by the numeral 8, is secured to the under side of the forward end of the car 6 and since the co-acting coupling member secured to a car, adapted to be coupled with the car 6, not shown, is of the same construction as the member 8, a description of one air hose coupling member 8 will suffice for both.

The air hose coupling member 8 is supported from the bottom of the forward end of the car by a rear supporting frame 9, adapted to support the rearmost end of the coupling member and a front supporting frame 10 adapted to support the forward end of said member 8. Both of said frames are arranged transversely of the car. The forward supporting frame 10 is substantially 95 square, the lower portion 11 of said frame being of substantially U-shaped construction. The upper or free ends of the arms of the U-shaped construction are bent outwardly and at right angles to the arms as at 12, 100 for fastening engagement with the car by means of bolts or the like whereby the U-shaped frame 11 is suspended from the bottom of the car. The upper portion of the supporting frame 10 consists of a brace bar 105 13 having its free ends bent downwardly and at right angles, whereby said angularly arranged ends 14 of the bar 13 are secured

to the arms 11 of the U-shaped frame to bridge the space between the free ends of said arms. Both the horizontal bottom 15 of the U-shaped frame 10 and the bar 13 are 5 provided each with a central vertical perforation for a purpose which will presently appear.

The rear supporting frame 9 is of substantially rectangular shape, the lower portion 10 16 thereof consisting of a U-shaped frame similar to the lower portion of the forward supporting frame 10. The free ends 17 of the arms of the U-shaped construction are bent outwardly and at right 15 angles to said arms, whereby said angularly arranged ends are secured to the under side of the car by bolts or other suitable securing means. The upper portion 19 of the rear supporting frame 9 also consists of a horizontal bar 19 having its free ends bent 20 downwardly and at right angles whereby said bar is secured between the free ends of the arms 16 of the U-shaped frame by means of rivets 20 or other suitable means. In 25 stead of the top and bottom of the rear supporting frame being provided with perforations, the vertical arms 16 of the U-shaped frame 9 are each provided with a central horizontal perforation, the purpose of which 30 will hereinafter appear.

The air hose coupling member 8 consists of a cylinder 21 passing through both the forward and rear supporting frames. A band 22 embraces the forward end of said 35 cylinder and said band is provided with oppositely disposed vertical extensions 22' carrying pintles 23. These pintles extend beyond the periphery of the band 22 and pass through the aligned perforations in the 40 lower portion 15 of the forward supporting frame 10 and the bracing bar 13 for pivotally supporting the forward end of the cylinder 21. This arrangement provides the 45 vertical pivot for the cylinder whereby the same may swing transversely of the car. It will of course be understood that the forward frame 10 as well as the rear frame 9 are of such size as to permit swinging movement of the cylinder within the frames. As 50 will be noted the band 22 is spaced from the upper and lower brace bars 13 and 15 respectively to permit the coupling member 8 to move vertically of the car when the forward car in a train strikes an uneven 55 joint between rails.

Referring more particularly to Fig. 3 of the drawings, the numeral 24 designates a pair of substantially semi-circular members adapted to embrace the rear portion of the 60 cylinder 21, and the free perforated ends of the members 24 are bent outwardly of the cylinder 21. The inner ends of these rods 25 are each enlarged and provided with a vertical opening to aline with the vertical 65 perforations in the outwardly bent free ends

of the semi-circular members 24. Bolts 26 are then passed through the perforations in the free ends of the semi-circular members and the openings in the enlarged inner ends of the guide rods 25. The guide rods pass 70 through and operate in the horizontal perforations in the vertical arms of the rear supporting frame 9 whereby the rear end of the cylinder 21 may move transversely of the car. A coil spring 27 is arranged upon 75 each guide rod 25, one end of the spring abutting with the vertical arms of the rear supporting member 9, while the opposite ends are adapted to abut with the enlarged inner ends of the rods 25. These springs 80 normally retain the cylinder 21 in the position whereby it extends longitudinally of the car.

Each end of the cylinder 21 is provided with an outwardly extending annular flange 85 28 to form a seat for the forward cylinder head 29 and the rear cylinder head 30. Bolts 31 or other suitable securing means pass through the cylinder head and the annular flanges 28 for detachably securing the 90 heads of the cylinder. The rear cylinder head is provided with a central threaded opening which engages with a threaded end of an air pipe 32. This pipe 32 carries an emergency cut off valve 33. Connected to 95 the valve and to the car's main air pipe 34, is a flexible tubing 35 which permits transverse swinging movement of the cylinder 21 in relation to the car 6. The forward cylinder head 29 is provided with a central opening 36, the lower portion or edge of which is cut away as at 37, more clearly shown in Fig. 5, to form an arcuate slot for a purpose which will presently appear.

As more clearly shown in Fig. 4, the hollow piston 38 operates within the cylinder 21 and is normally held in the forward end of said cylinder by a coil spring 39. The spring is positioned in the rear part of the cylinder 21 and one end of the spring abuts 105 with the rear end of the hollow piston 38, while the opposite end of the spring abuts with a ring 40. This ring is held in engagement with the rear cylinder head 30 under the tension of the spring and may be readily 110 removed from the cylinder if desired. The rearmost end of the hollow piston 38 is provided with an annular flange 41 having packing rings 42 therein for engagement with the inner wall of the cylinder 21. I 115 also provide an annular flange 43 upon the piston 38 adjacent the forward end thereof, which flange normally engages the forward cylinder head 29 by means of the coil spring 39 exerting a forward pressure upon the 120 cylinder 38. This annular flange 43 is also provided with a packing ring 44 so that it is impossible for air to escape from the cylinder through the slot 37. It will be clearly 125 seen from this arrangement that the hollow 130

piston 38 may reciprocate within the cylinder 21 and accordingly absorb shocks by one coupling member coming into engagement with the co-acting member.

5 As more clearly shown in Figs. 4 and 5 of the drawings, the movable piston 38 is provided with a longitudinally extending rib 45, which operates in the slot 37 in the forward cylinder head 29. This rib 45 is positioned forwardly of the angular flange 43 and upon the piston 38. This rib 45 and slot 37 arrangement makes it possible for the cylinder 21 to rock with the motion of the train and not affect the piston 38 when 10 the coupling members are coupled.

15 The forward end of the hollow piston 38 extends through and beyond the opening 36 in the forward cylinder head 29 and the outermost end of the piston is provided with 20 external screw threads for engagement with the coupling head designated in general by the numeral 46. The body portion 47 of the head is tubular and is provided with internal screw threads for engagement with the outer 25 screw threads of the hollow piston 38. Slightly forward of the threaded end of the body portion 47 is an interior annular flange 48 forming a valve seat. Extending forwardly of the body portion 47 of the head, 30 is an upper forwardly extending hollow jaw 49 which communicates with the tubular body portion 47. As more clearly shown in Fig. 4, the side wall 50 of the jaw 49 is provided with an air outlet opening or port 35 51. The outside wall 52 of the jaw 49 inclines forwardly and slightly inwardly, then inclines inwardly at a greater angle as at 53. The forward end of the side wall 50 of the jaw 49 inclines outwardly as at 54 40 to provide a wedge shaped nose upon the forward end of the jaw 49. The side wall 50 of the jaw 49 is provided with a transverse or portion 55, as more clearly shown in Fig. 6 of the drawings, and the forward 45 face of this portion is provided with a threaded recess 56. Communicating with this threaded recess is an opening 57 to form the horizontal guide opening for the valve stem 58. The rear end of the valve stem 50 extends rearwardly of the portion 55 and is provided with a valve 59, which seats upon the valve seat 48 in the body portion of the coupling head. A packing nut 60 is received in the threaded recess 56 of the de- 55 pending portion 55 and has a central opening through which the valve stem 58 reciprocatcs. The forward end of the valve stem extends forwardly and beyond the packing nut 60 so that said end is arranged 60 slightly to the side of the wall 50 of the jaw 49. This end of the valve stem is provided with an enlargement 61, the side face 62 of which engages the face 50 of the side wall of the jaw 49. The forward face 62' 65 of this enlargement inclines rearwardly from

the wall 50 to provide an abutment for the portion 54 of the lower jaw of the co-acting coupling head 49' and is more clearly shown in Fig. 4 of the drawing. It will be noted that the jaw 49' of the co-acting coupling head is the same as the jaw 49 of the coupling head just described. A spring 63 is positioned upon the forward end of the valve stem between the enlargement 61 and the inwardly extending portion 64 of the opposite jaw 65. One end of the spring abuts with the packing nut 60 while the opposite end of the spring abuts with the enlargement 61, whereby the valve 59 is normally positioned upon its seat, thereby closing the passage-way between the piston 38 and the hollow jaw 49.

60 The flange portion 64 of the jaw 65 is provided with a threaded opening 66 to receive the packing nut 60. From Fig. 6 it will be seen that substantially one-half of the packing nut engages with the threaded recess 56 of the upper jaw 49, while the other half of the nut engages with the threaded recess 66 of the other jaw. It is by 65 this means that the jaw 65 is partially and detachably supported by its co-acting jaw. This jaw 65 is preferably solid and extends forwardly and longitudinally of the piston 38 in spaced relation to its upper jaw, where- 70 by a pocket is formed between the jaws for receiving the jaw 49' of the co-acting coupling head when the heads are coupled. The vertical inside surface of the jaw 65 inclines forwardly and outwardly from the 75 flange portion 64, as at 67, then inclines in the same direction as at 68 at a smaller angle to the forward end of the jaw. The rear portion of this jaw is detachably secured to the other jaw by means of bolts 69.

70 It is to be understood that the jaw 49 is identically the same as the lower jaw 49' of the co-acting coupling head.

75 In operation, assuming that the coupling heads are coming together as shown in Fig. 4, the wall 52 of the jaw 49' contacts with and slides inwardly on the inclined surface 68 of the jaw 65. As the jaw 49' moves farther inwardly of the pocket between the two jaws of the co-acting coupling head, the 80 surface 52 of the jaw 49' will abut with and ride upon the inclined surface 67 of the jaw 65. At the same time, the nose or inclined portion 54 of the jaw 49' abuts with the inclined forward surface 62' of the enlargement 61 formed upon the forward end of the valve stem. This action of course, moves the valve stem rearwardly of the coupling head and moves the valve 59 from its seat to permit air to pass through the pistons 38 into the hollow jaw 49 then through the air outlet passage-way 51 and into the hollow jaw 49' of the co-acting coupling head. By providing the inclined surfaces 85 52 and 53 upon the jaws 49 and 49' and their 90 95 100 105 110 115 120 125 130

coöperation with the inclined surfaces 67 and 68 of the coacting jaw 65 it will be seen that the closer the coupling heads come together the closer the walls 50 will be brought into engagement with one another. This of course, provides a tight fit between the air outlet passage-ways 51.

When the coupling heads come into engagement with one another, the hollow pistons 38 are moved rearwardly, this action being opposed by the compression of the spring 39. After the heads have been coupled, this spring exerts a forward force upon the hollow piston, thereby holding the coupling heads in close engagement with one another. As stated before, the annular flange 43 of the piston prevents excessive forward movement of said piston by abutting with the forward cylinder head 29. When the heads are coupled and the cars begin to rock, it will be seen that the supporting frames 9 and 10 together with the cylinder 21 will rock with the car. As the forward cylinder head is provided with the arcuate slot 37, in which the rib 45 operates, the piston 38 will not be affected by the rocking movement of the train, since the slot 37 will move about the rib 45.

As the coupled cars move around a curve, it will be seen that the cylinder 21 will swing transversely of the car. The forward end of the cylinder 21 will swing upon its vertical pivot in the supporting frame 10, while the rear end of the cylinder will be permitted to move to either side by the guide rods 25 operating through the vertical arms of the rear supporting frame 9. After the cars have cleared the curve and are upon a straight track, the springs 27 on the guide rods 25 will replace the cylinder 21 to its normal position.

The foregoing description and accompanying drawings have reference to what might be considered to be the preferred or approved form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

1. In the combination, a pair of coupling members, a coupling head carried by each member, and having an air passage therethrough, a normally closed valve in said head, a pair of jaws carried by each head, one jaw having an opening therein, said jaw being further provided with a threaded recess communicating with said opening, the co-acting jaw having a threaded opening, a packing nut threaded into said threaded recess and threaded opening in the jaws for detachably connecting the jaws of each head,

and a valve stem passing through the opening in the jaw and through the threaded recess and through said packing nut.

2. In the combination, a pair of coupling members, normally extending longitudinally of a car, means for permitting air to automatically pass through said members when they are coupled, means for vertically pivoting the forward ends of said members, a pair of oppositely disposed horizontal guide rods pivoted to the rear end of each member, a rear supporting frame for each member in which said rods operate whereby said members may swing transversely of the car, and means for normally retaining the coupling members in their normal position.

3. In the combination, a pair of coupling members each including a cylinder permitted to swing transversely of a car, a piston normally retained in the forward end of said cylinder whereby the piston moves rearwardly thereof when the coupling members are being coupled, said cylinder having an arcuate slot, means on the piston and operating in said slot whereby rocking movement of the cylinder is prevented from rocking said piston, and means for permitting air to automatically pass through the coupling members when they are coupled.

4. An air hose coupling comprising a hollow cylinder, an air pipe connected to a car and to the rear end of said cylinder, a hollow piston operating in said cylinder and passing through the forward end thereof, said piston having an open rear end within said cylinder, said piston being normally retained in the forward end of said cylinder, and a coupling head secured to the forward end of said piston.

5. In the combination, a pair of coupling members normally extending longitudinally of a car, means for permitting air to automatically pass through said members when they are coupled, means for vertically pivoting the forward ends of said members to the car, the rear supporting frame having vertical side arms, each arm being provided with an opening, a pair of oppositely disposed horizontal guide rods pivoted to the rear end of each member and passing through the openings in the vertical side arms of said frame, and a coiled spring mounted upon each rod for abutment with said member and a side arm of the frame to normally retain said coupling members in their normal position.

6. In the combination, a pair of coupling members, each including a cylinder permitted to swing transversely of a car, a piston normally retained in the forward end of said cylinder and extending through the forward end of said cylinder whereby the piston may move longitudinally of car, said piston having annular flanges thereon for engagement with the inner walls of the

cylinder to prevent air from passing around said piston, the forward end of said cylinder being provided with an arcuate slot, and a longitudinally extending rib on said piston 5 and operating in said slot whereby rocking movement of the cylinder is prevented from rocking said piston.

In testimony whereof I affix my signature in presence of two witnesses.
